UNITED STATES PATENT OFFICE.

GIOACHINO CARLO PRECERUTTI, OF TURIN, ITALY.

APPARATUS FOR WASHING EYES.

1,331,374.

Specification of Letters Patent. Patented Feb. 17, 1920.

Application filed July 17, 1919. Serial No. 311,540.

To all whom it may concern:

Be it known that I, GIOACHINO CARLO PRECERUTTI, a subject of the King of Italy, and resident of Turin, Italy, have invented

5 certain new and useful Improvements in Apparatus for Washing Eyes, of which the following is a specification.

The present invention has reference to an apparatus by means of which it is possible 10 to wash the eyes without bringing the hands in contact therewith, and adapted to be used not only for therapeutic purposes but also to remove any foreign body that may have passed under the eyelids or that may adhere 15 to the cornea.

The improved apparatus also enables persons attacked by gas and more particularly by so-called lachrymose gas, to immediately wash the eyes whereby the immediate or 20 subsequent action of these gases upon the organs of vision is either counteracted or modified.

For this purpose apparatus according to the invention comprises an eye vessel which 25 by completely closing the orbital cavity keeps the eyelids open, the said vessel communicating with a receptacle such for instance as a rubber ball so as to enable a jet of liquid contained in the said receptacle to 30 be directed upon the ball of the eye. The eye vessel is in the form of an almost semi-ellipsoidal cup and comprises in its interior two guards adapted to exercise pressure upon the eye-lids at such points as to compel 35 them to uncover the globe of the eye when said vessel is applied to the eye.

The accompanying drawing shows a constructional form of apparatus according to the invention.

40 Figure 1 is a side elevation of the eye vessel of the apparatus; Fig. 2 is a perspective view of the complete apparatus and Fig. 3 is an internal view of the eye vessel.

As will be seen from these figures the apparatus 45 comprises an eye vessel 1 of semi-ellipsoidal form the edge of which is curved and of such dimensions as to adapt itself to the orbital cavity and to close such cavity completely.

50 The end 2 of the vessel 1 which, when in use, is nearest the temple is adapted to laterally close the orbital cavity.

Inside the eye vessel are two guards 3 extending parallel or almost parallel to each 55 other and projecting slightly beyond the edge of the shell as shown in Fig. 1. The

distance apart of the said guards is such that on applying the vessel to the eye the pressure that they exercise upon the eye-lids when closed tends to open them and cause 60 them to slide over the ball of the eye.

The vessel 1 at the side of the end portion 2 is formed with a hole 4 to which there is connected a small tube 5 suitably inclined in such a direction that a jet of liquid issuing 65 from the said tube into the vessel 1 may be directed upon the ball of the eye.

To the outer end of the tube 5 is connected a rubber tube 6 that communicates with a bulb 7 adapted to hold the liquid with which 70 the washing is to be effected.

In order to use the apparatus all that is necessary is to apply the edge of the vessel 1 to the closed eye and exercise a slight pressure until the orbital cavity is completely 75 closed by the vessel. During such an operation the guards 3 cause the opening of the eyelids so that upon compressing the bulb 7 there is directed upon the uncovered ball of the eye a jet of the desired liquid which carries away any foreign bodies that may have 80 got under the eye-lids or that adhere to the cornea. Such liquid comes into contact with all the parts likely to become infected or inflamed. The same liquid contained in the 85 bulb 7 may be used for washing both eyes, care being taken, after having washed one eye, to allow the bulb to expand progressively so that it can again suck up the liquid contained in the vessel 1. Such an operation 90 is facilitated by the fact that the hole 4 is located on one of the sides of the vessel 1 and can thus be located at the lower part of the vessel for one of the eyes and this eye should be the first one to be washed. 95

The inner surface of the vessel 1 may be either smooth or roughened so as to retain any small foreign bodies which are carried along by the jet of liquid, and its form may be different to that shown provided that it 100 be such as to completely close the orbital cavity and to compel the eye-lids to remain open when the apparatus is in position.

It will be readily understood that with the aid of the improved apparatus anyone is 105 able effectively to wash the eyes without having to bring his hands into contact with them thus avoiding any irritation of the eye.

What I claim as my invention and desire to secure by United States Letters Patent 110 is:

1. An apparatus for washing eyes com-

prising a vessel the edge of which is adapted to close the orbital cavity, members in the interior of said vessel and projecting from its edge, adapted to act on the eyelids to open the same, and means connected with said vessel and adapted to direct a liquid jet into said vessel on the eye ball.

2. An apparatus for washing eyes comprising a vessel the edge of which is adapted to close the orbital cavity, two longitudinal guards in the interior of said vessel and projecting from its edge, adapted to act on the eyelids to open the same, and means connected with said vessel and adapted to direct a liquid jet into said vessel on the eye ball.

3. An apparatus for washing eyes comprising a vessel the edge of which is adapted to close the orbital cavity, members in the interior of said vessel and projecting from its edge, adapted to act on the eyelids to open the same, an inclined pipe opening in said vessel and means connected with said pipe and adapted to direct a liquid jet through the same into said vessel on the eye ball.

25

4. An apparatus for washing eyes comprising a vessel the edge of which is adapted to close the orbital cavity, members in the interior of said vessel and projecting from its edge, adapted to act on the eyelids to open the same, an inclined pipe opening in said vessel at a side thereof and means connected with said pipe and adapted to direct a liquid jet through the same into said vessel and laterally on the eye ball.

35

5. An apparatus for washing eyes comprising a vessel adapted to close the orbital cavity and having a semi-ellipsoidal shape, two guards in said vessel adapted to act on the eyelids to open the same, said guards being located parallel with the long axis of said vessel, an inclined pipe opening in said vessel at a side with regard to said guards and axis, and means connected with said pipe and adapted to direct a liquid jet through the same into said vessel and laterally on the eye ball.

40

Signed at Turin, Italy, June 30, 1919.

GIOACHINO CARLO PRECRUTTI,
